ORIN LOREN BRISTOL AND ALBERT FRANK VORCE, OF GRAND RAPIDS, MICHIGAN; SAID BRISTOL ASSIGNOR, BY MESNE ASSIGNMENTS, TO SPARTA MFG. CO., OF GRAND RAPIDS, MICHIGAN.

COIN-CONTROLLED MECHANISM FOR VENDING APPARATUS.

1,135,934.

Specification of Letters Patent. Patented Apr. 13, 1915.

Application filed July 15, 1914. Serial No. 851,147.

To all whom it may concern:

Be it known that we, ORIN L. BRISTOL and ALBERT F. VORCE, citizens of the United States, residing at Grand Rapids, in the county of Kent, and State of Michigan, have invented a new and useful Coin-Controlled Mechanism for Vending Apparatus, of which the following is a specification.

This invention has reference to improvements in coin controlled mechanism for vending apparatus, and its object is to provide a mechanism of the character stated which shall be free from liability of surreptitious operation or extraction of coins already inserted, and shall further be free from liability of inoperativeness due to clogging of the coins or the deflection of the coins from the proper channels.

In accordance with the present invention there is provided a manipulating member for the vending apparatus and this manipulating member is under the control of a lock mechanism which may be released by an inserted coin, and this lock mechanism is controlled by springs so that it may not be operated by simply inverting or otherwise placing the structure, and the lock mechanism is so constructed that by means of pawl and ratchet devices the manipulating member cannot by sudden impulses or jerks be moved actively to any extent at all. Furthermore the coin chute is so constructed that coins will readily find their way into proper position with relation to the operating mechanism without clogging and cannot be readily withdrawn from the locking mechanism after having performed the proper office therein.

The invention will be best understood from a consideration of the following detailed description taken in connection with the accompanying drawings forming a part of this specification with the further understanding that while the drawings show a practical form of the invention it is susceptible of other practical embodiments and is therefore not limited to any strict conformity with the showing of the drawings, but may be changed and modified so long as such changes and modifications mark no

material departure from the salient features of the invention.

In the accompanying drawings:—Figure 1 is a front elevation of a portion of a vending machine constructed in accordance with the present invention. Fig. 2 is a section on the line 2—2 of Fig. 1. Fig. 3 is a rear elevation of the structure shown in Figs. 1 and 2 with part of the casing in section and other parts broken away. Fig. 4 is a view similar to Fig. 3 but showing a different phase of operation and also indicating the coin chute in section. Fig. 5 is a section on the line 5—5 of Fig. 3. Fig. 6 is a section on the line 6—6 of Fig. 1 with parts shown in elevation and drawn to a larger scale. Fig. 7 is a perspective view of one of the pawls employed in the structure. Fig. 8 is a perspective view of another one of the pawls.

Referring to the drawings there is shown a portion of a casing 1 which may be of any construction suitable for the purpose, and as the construction of this casing does not enter into the present invention, detailed description of the casing need not be given. Carried by the casing preferably exterior thereto is a vending mechanism 2, the construction of which does not enter into the present invention, and, therefore, needs no special description. This vending mechanism in the particular instance shown may be of a type whereby perfume can be vend- ed and as the perfume is usually in liquid form, an atomizer structure 3 may be provided. This atomizer structure is under the control of a manipulating member 4 having a push piece 5 on one end of a slide 6 which is mounted on one face of one wall of the casing, and this wall may be termed the front wall. The slide 6 is also under the control of an angle lever 4^a having a handle 5^a and an arm 6^a in engagement with the push piece 5 so that the lever may be used instead of the push piece to actuate the slide. Through the front wall of the casing there is produced a narrow elongated slot 7 with which the slide 6 is coincident and on the other or rear face of the front wall of the casing there is mounted a plate 8 connected to the slide 6 by rivets 9 or 100

other suitable connecting devices extending through the slot 7, so that the slide 6 and plate 8 are connected together for simultaneous movement, and when the slide 6 is caused to move in the direction of the length of the slot 7 by a force applied to the push piece 5 the plate 8 participates in such movement. The arrangement is such that when a propelling force is applied to the push piece 5 and the slide 6 is free to move in the proper direction the atomizer 3 is operated in a manner to produce a spray of perfume which may be caught upon a handkerchief which it is desired should be perfumed. The plate 8 is in the general form of an elongated rectangle with fingers 10, 11, 12 and 13 at the respective corners. The finger 10 is bent into spaced returning relation to one long side of the plate 8, and as will hereinafter appear, serves as a guard. The finger 11 is an angle finger extending from the plate 8 in a direction lengthwise of the latter and then away from the corresponding long side of the plate in a direction perpendicular thereto and has a function which will hereinafter appear. The finger 12 extends from the corresponding long side of the plate 8 in a direction substantially perpendicular thereto and serves as a stop finger, as will hereinafter appear. The finger 13 extends from the same long side of the plate 8 as the finger 12, but from the end of the plate remote from the finger 12 and in a direction substantially perpendicular to the long side of the plate, and this finger is adjacent to the plate 8 so bent as to lie at a greater distance from the inner face of the front of the casing 1 than the plate, so as to be spaced from such inner face. The bent portion of the finger is indicated at 14. From this bent portion the finger is continued first in a direction parallel with the corresponding long side of the plate 8 and then is continued along the corresponding end of the plate 8 substantially parallel therewith to a point substantially coincident with the other long side of the plate 8 where the finger terminates in a tooth 15 projecting in a direction away from the plate 8, and where the tooth 15 joins the finger 13 there is produced a notch 16 for a purpose which will presently appear.

Connected to the inner face of the casing 1 by a pivot 17 is a plate-like pawl 18 terminating at a point remote from the pivot 17 in a toe 19 normally projecting toward the finger 13 and the pawl 18 is also provided with a tooth 20 overlying the pawl and spaced from the inner face of the front of the casing 1 to an extent to engage the tooth 15 and lodged at its free end in the notch 16. The pawl 18 at a point remote from the toe 19 is provided with an ear 21 to which is connected one end of a spring 22,

the other end of this spring being made fast to the casing 1 by a stud 23. The tendency of the spring 22 is to maintain the tooth 20 in the notch 16 and against the tooth 15 and when the parts are in this position the plate 8 is locked against longitudinal movement by the engagement of the tooth 20 in the notch 16 and by the engagement of one of the rivets 9 with the corresponding end of the slot 7. This locks the plate 8 and the slide 6, as well as the manipulating member 4 against extended movement in either direction.

Pivoted to the inner face of the front of the casing adjacent the plate 8 is a pawl 24 terminating at one end in a tooth 25 and a shoulder 26 adjacent thereto. Also pivoted to the inner face of the front of the casing is another pawl 27 terminating in a tooth 28 in position to engage the shoulder 26 of the pawl 24 adjacent the tooth 25. The pawl 24 and the pawl 27 are each mounted in the casing adjacent that long edge of the plate 8 from which the fingers 10 and 11 project and for an appropriate length of such long side it is formed with ratchet teeth 28^a in position to be engaged by the tooth 25 of the pawl 24 and so disposed that when so engaged the plate 8 is held against movement toward the pawl 18.

The other long edge of the plate 8 is formed with a longitudinal series of ratchet teeth 29 in position to be engaged by a tooth 30 on one end of a pawl 31 pivoted to the inner face of the front of the casing adjacent the plate 8. The pawl 31 has a continuation on that side of its pivot remote from the tooth 30 and there terminates in another tooth 32, while pivoted adjacent that end of the pawl 31 having the tooth 32 is an arm 33 provided with an intermediate notch 34 in which the tooth 32 may lodge under conditions to be described. The pawl 27 and the arm 33 are connected together by a spring 35 so arranged as to tend to move the arm 33 toward the pawl 31 and the pawl 27 toward the pawl 24. That end of the pawl 31 formed with the tooth 30 is connected by a spring 36 to the pawl 24 and the tendency of this spring is to move the tooth 30 of the pawl 31 into engagement with the ratchet teeth 29 and the tooth 25 of the pawl 24 into engagement with the ratchet teeth 28^a.

Fast to the inner face of the front wall of the casing 1 is a coin chute 37 having a portion 38 constituting a coin guide and another portion 39 serving as an abutment for a coin, while between these two parts 38 and 39 there is an opening 40 in part covered by a projecting lip 41. The opening 40 and lip 41 serve for the escape of a coin from the chute to the space provided between the finger 10 and the pawl 18, the coin

lodging upon the toe 19. The receiving end of the coin chute 37 is higher than the escape end, so that a coin will gravitate to the coin controlled mechanism, and produced through 5 the front plate of the casing is a slot 42 for the reception of the coin, this slot being of appropriate length and thickness. At one side of the slot 42 there is formed a wing 43 tending to direct the coin away from the 10 opening 40 as it is introduced into the coin chute, so that there is little chance of extracting a coin after having been once introduced into the chute.

In Fig. 3 of the drawings there is shown 15 a coin 44 which is assumed to have been already introduced into the chute through the coin slot 42 and to have gravitated into the space between the finger 10 and pawl 18, and lodging on the toe 19 between which 20 and the corresponding portion of the finger 10 the space is too small to permit the further passage of the coin. If now pressure be applied upon the manipulating portion or head 4 of the slide 6, the finger 10 through 25 the coin will move the pawl 18 about its pivot 17 and against the normal tendency of the spring 22, so as to carry the tooth 20 out of the notch 16, when, because of the relation of the pivot 17 to the finger 13, the 30 tooth 20 will simply ride along the corresponding portion of the finger 13 permitting the plate 8 to travel along the slot 7. This movement is not at all resisted by the tooth 30 since the latter simply trails along 35 the ratchet teeth 29, these teeth being pointed in the proper direction for the purpose. The teeth of the ratchet 28^a are, however, pointed in a direction which if engaged by the tooth 25 of the pawl 24 would hold the 40 plate 8 against further progressive movement under the pressure exerted upon the manipulating head 4. However, in the normal operation of the parts the pawl 24 is held out of active position and against the 45 normal tendency of the spring 36 by the spring 35 and consequently under these conditions the pawl 24 is inactive. The progressive movement of the plate 8 is continued until the parts assume about the position shown in Fig. 4 where the coin 44 has 50 traveled along the finger 10 and pawl 18 until the space between these two parts where occupied by the coin has increased until the coin may escape by gravity or be 55 discharged by the pressure being exerted. Just prior to the parts reaching the position shown in Fig. 4, in which figure the limit of travel of the movable parts in the active direction is indicated, the tooth 30 is engaged 60 by the finger 12 and this tooth being suitably beveled the pawl 31 is rocked on its pivot against the action of the spring 36 putting the latter under greater tension than before. At the same time the tooth 32 which

normally is to one side and out of the notch 65 34 moves along the arm 33 until coincident with the notch 34 when the spring 35 causes a movement of the arm 33 sufficient to lodge the tooth 32 in the notch 34 and the tooth and notch are so related as to cause a locking 70 of the pawl 31 against the action of the spring 36.

Simultaneously with the actions so far described with respect to the pawl 31 and arm 34, the finger 11 is brought into engagement 75 with the pawl 27 in a manner to rock this pawl against the action of the spring 35 and carry its tooth 28 out of engagement with the shoulder 26, whereupon the tension of the spring 36 causes a rocking of the pawl 24 80 until its tooth 25 engages behind the last one of the teeth of the ratchet 28^a toward the finger 11. The pawl 24 then arrests further movement of the plate 8 and the actuating means therefore in the active direction. 85 Now, if pressure upon the manipulating head 4 be relieved, the spring 22 which by the rocking of the pawl 18 during the active movement of the plate 8 has been put under additional tension, causes the tooth 20 to act 90 on the finger 13 in a manner to return the plate 8 toward the inactive position. This inactive movement of the plate 8 carries the finger 11 away from the pawl 27 and the finger 12 away from the tooth 30, but the 95 tooth 28 of the pawl 27 cannot reach the shoulder 26 of the pawl 24 since this pawl has been moved to too great an extent to permit such action. The pawl 31 is held with its tooth 30 away from the ratchet 29 100 by the locking of the tooth 32 in the notch 34 and the plate 8 is free to return to the full extent of its inactive movement. Just before the limit of such inactive movement is reached, the end of the plate 8 carrying the 105 finger 12 engages the corresponding end of the arm 33 and moves it out of engagement with the pawl 31, so that the spring 36 may act on the pawl 31 to carry the tooth 30 into the path of the ratchet 29, while a terminal 110 shoulder 45 of the ratchet teeth 28^a engages and rocks the pawl 24 in a direction to carry its tooth 25 out of the path of the teeth 28 and the tooth 28 of the pawl 27 moves into engagement with the shoulder 26 115 and so locks the pawl 24 in the inactive position. However, when the parts have again reached the position shown in Fig. 3 the tooth 20 snaps into the notch 16 under the action of the spring 22 and the plate 8 is 120 once more locked against active movement and can only be again placed in the active condition by the insertion of a proper coin.

The movement of the slide 6 brings about the desired vending, but the vending side of 125 the machine does not enter into the present invention and specific description thereof is deemed unnecessary.

The pawl 31 prevents any action of the manipulating means less than a full stroke, while the pawl 24 prevents active movement of the manipulating means after the return stroke has begun, so that any attempt to manipulate the device other than in the proper way is prevented by one or the other of the two pawls, while the pawl 18 prevents any manipulating of the device unless a suitable coin or token be introduced. No amount of shaking of the device or no turning of the device in different positions will result in unlocking the coin controlled mechanism, so that the only recourse is to introduce a proper coin if it be desired to obtain material from the vending side of the machine.

The finger 10 is so arranged as to move across the opening 40 of the coin chute to an extent to prevent any return of the coin into the chute after the active movement of the manipulating means has commenced, even though the machine be inverted, while the finger 10 where joining the plate 8 is provided with an offset 46 to cause an enlargement of the space in which the coin is lodged to facilitate the discharge of the coin as the parts approach the limit of active movement.

30 What is claimed is:—

1. In a coin controlled mechanism for vending machines, a reciprocable slidable member provided with accessible means for its manipulation, a separate oppositely acting locking means for the slidable member, holding means for the locking means arranged in the path of the slidable member at the ends of its travel for operation thereby, and another locking means for the slidable member active thereto in the absence of a proper coin and yieldable on the insertion of a proper coin to a manipulating force applied to the slidable member.

2. In a coin controlled mechanism for vending machines, a slidable member having oppositely directed ratchet teeth, pawls, one for each set of ratchet teeth, locking members for the pawls for holding them in the inoperative position, actuating members for the pawls carried by the slidable member, and a locking device in the path of the slidable member and yieldable to active movement of the slidable member through the intermediary of an inserted coin.

3. In a coin controlled mechanism for vending machines, a suitable member, separate oppositely-acting pawl and ratchet means for locking the slidable member against movement in either direction, means controlled by the slidable member for locking one or the other of the pawl and ratchet locking means in the inactive position, and means for locking the slidable member against active movement; said last-named

means being yieldable to a force applied thereto by the slidable member through an inserted coin.

4. In a coin controlled mechanism for vending machines, a slidable plate provided with oppositely directed ratchet teeth, pawls in operative relation to the ratchet teeth, locking devices, one for each pawl, for holding them in the inoperative position, said locking devices being located in the path of the slidable member at respective limits of its movement in opposite directions, and a pawl device normally in the path of the slidable member in the direction of its active movement for preventing such active movement, said last-named pawl device being yieldable to the slidable member through the intermediary of an inserted coin.

5. In a coin controlled mechanism for vending machines, a slidable plate provided at the corners with projecting fingers and along opposite sides with oppositely directed ratchet teeth, pawls, one for each set of ratchet teeth, locking members individual to the pawls and in the path of certain of the fingers of the slidable member, spring connections between the pawls, spring connections between the locking members, another pivoted pawl in the path of another of the fingers of the slidable member on its active movement, said pawl and finger having coacting locking means, and a spring for the last-named pawl tending to move it into locking engagement with the respective finger of the slidable member.

6. In a coin controlled mechanism for vending machines, a slidable plate provided at the corners with projecting fingers and along opposite sides with oppositely directed ratchet teeth, pawls, one for each set of ratchet teeth, locking members individual to the pawls and in the path of certain of the fingers of the slidable member, spring connections between the pawls, spring connections between the locking members, another pivoted pawl in the path of another of the fingers of the slidable member on its active movement, said pawl and finger having coacting locking means, and a spring for the last-named pawl tending to move it into locking engagement with the respective finger of the slidable member, said mechanism being also provided with a coin directing chute located to deliver a coin between the last named pawl and the last-named finger of the slidable member.

7. In a coin controlled mechanism for vending machines, a slidable plate having oppositely directed ratchet teeth on opposite edges and provided at the corners with fingers projecting in different directions, one of the fingers having a terminal portion provided with a notch, a pawl having a tooth in

operative relation to one set of ratchet teeth and also provided with a shoulder at the toothed end, and the other pawl having a tooth in operative relation to the other set of ratchet 5 teeth and at the end remote from said tooth being provided with another tooth, a spring connecting those ends of the pawls adjacent the ratchet teeth, a lock member for the first-named pawl movable into and out of engagement with the shoulder thereon, a notched lock member for the second named pawl movable into and out of engagement with the second-named tooth of the second named pawl, spring connections between the lock 10 members, and said lock members being located in the path of fingers on the slidable member, and another pawl in the path of the notched finger and having a tooth adapted to said notch, said last named pawl being 15 provided with a controlling spring having a normal tendency to hold its tooth in the notch in the finger and with means for arresting an inserted coin in position to be engaged by the corresponding end of the slid- 20 able member.

8. In a coin controlled mechanism for vending machines, a slidable member having accessible actuating means and a pivoted member having its pivot point to one side 30 of the line of movement of the slidable member and provided with a controlling spring tending to hold the pivoted member in end engagement with the slidable member, said controlling spring also acting through the 35 pivoted member to move the slidable member toward its normal position, and said pivoted member and slidable member having coacting parts for holding a coin between them and other coacting parts for normally locking 40 the slidable member against active movement in the absence of a coin.

9. In a coin controlled mechanism for vending machines, a slidable member, a pivoted member in the line of movement of 45 the slidable member, said pivoted member and slidable member having coacting parts for the reception of a coin between them, and a spring for the pivoted member tending to move said pivoted member toward the 50 slidable member and to actuate the slid- able member toward its normal position, said slidable and pivoted members having coacting parts for holding the slidable mem- 55 ber in the normal position in the absence of an inserted coin.

10. In a coin controlled mechanism for vending machines, a slidable member, a pivoted member having its pivot point at one side of the line of movement of the slid- 60 able member, and a spring for the pivoted member tending to move the same toward the slidable part and to actuate the slidable member toward its normal position, said slidable member and pivoted member hav-

ing coacting parts for holding the slidable 65 member in the normal position in the absence of an inserted coin, said coacting parts comprising a tooth on the pivoted member and a notched finger on the slidable member. 70

11. In a coin controlled mechanism for vending machines, a slidable plate provided at one end with a curved finger and with another finger in spaced relation to the same end of the slidable member carrying the 75 curved finger, and a pivoted member in spaced relation to said end of the slidable member and provided with a tooth adapted to engage the second named finger, the latter having a notch in position to receive said 80 tooth, and means for directing a coin into the space between the slidable member and the pivot member.

12. In a coin controlled mechanism for vending machines, a slidable plate provided 85 at one end with a curved finger and with another finger in spaced relation to the same end of the slidable member carrying the curved finger, and a pivoted member in spaced relation to said end of the slidable 90 member and provided with a tooth adapted to engage the second named finger, the latter having a notch in position to receive said tooth, and means for directing a coin into the space between the slidable member and 95 the pivoted member, the second named finger of the slidable member and the tooth on the pivoted member being offset with relation to the members carrying them and the pivoted member being provided with a coin 100 receiving toe to hold an inserted coin between the two members.

13. In a coin controlled mechanism for vending machines, a slidable member and a pivoted member normally spaced apart a 105 distance greater than the diameter of a suitable coin, said members having the coin engaging portions in line one with the other, with the slidable member provided with a notched finger extended toward the other 110 member to one side of the coin space between them, and with the pivoted member provided with a tooth similarly extended toward the slidable member and normally lodged in the notch in the finger to lock the 115 slidable member against manipulation, said pivoted member having a coin support normally in the path of an inserted coin and also provided with elastic constraining means permitting it to yield to a force applied thereto by the slidable member through an inserted coin in a direction to cause the unseating of the tooth from the notch. 120

14. In a coin controlled mechanism for 125 vending machines, a slidable member, accessible means for its manipulation includ- ing an angle lever having an arm in posi-

tion to move the slidable member and another arm in position to be actuated by the operator of the machine, separate oppositely acting locking means for the slidable member, and another locking means for the slid-
able member, active thereto in the absence of a proper coin and yieldable on the insertion of a proper coin to a manipulating force applied either directly to the slidable member or applied thereto through the lever.

In testimony that we claim the foregoing 10 as our own we have hereto affixed our signatures in the presence of two witnesses.
